(57) **CLAIM**

The ornamental design for the cord clip, as shown and described.

DESCRIPTION

FIG. 1 is a front elevation view of a cord clip showing my new design;

FIG. 2 is a top plan view of the cord clip of FIG. 1;

FIG. 3 is a front end view of the cord clip of FIG. 1;

FIG. 4 is a back end view of the cord clip of FIG. 1;

FIG. 5 is a side plan view of the cord clip of FIG. 1;

FIG. 6 is an opposite side plan view thereof of the cord clip of FIG. 1; and,

FIG. 7 is a bottom plan view cord clip of FIG. 1.

In the drawings, the broken lines form no part of the claimed design.
